UNITED STATES PATENT OFFICE

98,767

DESIGN FOR AN INKWELL DESK UNIT

Carey G. Gregory, Los Angeles, Calif.

Application August 10, 1935, Serial No. 58,073

Term of patent 7 years

To all whom it may concern:

Be it known that I, Carey G. Gregory, a citizen of the United States, residing at Los Angeles, in the county of Los Angeles and State of California, have invented a new, original, and ornamental Design for Inkwell Desk Unit, of which the following is a specification, reference being had to the accompanying drawing, forming part thereof.

Fig. 2 is a perspective view of the inkwell desk unit of my invention with the cover for the ink container removed; and

Fig. 3 is a perspective view of the cover of the inkwell desk unit removed from the ink container.

I claim:

The ornamental design for an inkwell desk unit as shown.

CAREY G. GREGORY.
